CLAIM

The ornamental design for a fencing bracket, as shown and described.

DESCRIPTION

FIG. 1 is a perspective view of a fencing bracket incorporating my design.

FIG. 2 is a front elevation view of the fencing bracket shown

FIG. 1, the rear elevation view being a mirror image thereof.

FIG. 3 is a top plan view of the fencing bracket shown FIG.

1, the bottom plan view being identical thereto.

FIG. 4 is a left side elevation view of the fencing bracket shown FIG. 1; and,

FIG. 5 is a right side elevation view of the fencing bracket shown FIG. 1.

The broken line areas represent portions of the fencing bracket that form no part of the claimed design.
